UNITED STATES PATENT OFFICE.

SAMUEL S. FOOTE AND JOSEPH C. MCKEE, OF CALDWELL, IDAHO.

DEBRANNING APPARATUS.

SPECIFICATION forming part of Letters Patent No. 738,669, dated September 8, 1903.

Application filed December 29, 1902. Serial No. 137,003. (No model.)

To all whom it may concern:

Be it known that we, SAMUEL S. FOOTE and JOSEPH C. MCKEE, citizens of the United States, residing at Caldwell, in the county of Canyon and State of Idaho, have invented certain new and useful Improvements in Debranning Apparatus; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in milling appliances, and especially in the provision of a feeding-coil which is adapted for the purpose of pressing or compacting grain within the cylinder, causing the same to choke and be in proper condition to be acted upon by a cone as a regulator or valve to retard the grain sufficiently to be operated upon.

More specifically the invention consists in the provision of a feeding-coil, the last turn of the coil being disposed at substantially right angles to the shaft on which it is carried for a distance equal to one-half of the circumference of the shaft and the extreme end bent at an inclination rearward to the twist of the coil.

The invention will be hereinafter fully described and then specifically defined in the appended claim and is illustrated in the accompanying drawings, which, with the letters of reference marked thereon, form a part of this application, and in which—

Figure 1 is a central vertical section through a feed-hopper and conveyer-box, showing the conveyer in elevation with the worm thereon. Fig. 2 is an enlarged detail view showing the shape of the bent end of the worm.

Reference now being had to the details of the drawings by letter, A designates a conveyer-box, and B a cylinder which is positioned adjacent thereto and has a bore the

wall of which is continuous with the inner wall of said conveyer-box, and C designates a hopper to the conveyer-box, and D is a shaft 50 which passes through an aperture in the conveyer-box and has thereon a coil conveying-worm E, which worm is of the ordinary construction, excepting the last turn of the coil, from the point F to F', is disposed with its 55 outer periphery in a plane at right angles to the length of the shaft instead of following the regular spiral course of the wing and the extreme end of the coil is bent back at an angle, as shown. By this provision of feeding-worm having the last turn of the spiral coil positioned as shown and described we are enabled to compact the wheat within the cylinder at such a consistency that it will be satisfactorily fed out through the flaring portion of the cylinder and the regulating-cone. With the ordinary form of conveyer a space is left between the end of the conveyer and the outlet for the wheat between the cone and concave, and in this space the bran from 70 wheat is mostly loosened and rubbed off, and with an ordinary conveyer trouble is met with in the material working irregularly and wheat would frequently come through without filling the cylinder tightly and without 75 choking; but by the provision of a conveyer embodying our invention the cylinder is kept compactly filled, which causes the debranning to be carried on more satisfactorily than with conveyers commonly in use. 80

While we have shown a particular detailed construction of apparatus embodying our invention, it will be understood that we may make slight alterations in the construction of the same without departing from the spirit 85 of the invention.

Having thus fully described our invention, what we claim as new, and desire to secure by Letters Patent, is—

A debranning apparatus comprising a box, 90 a cylinder communicating therewith, a shaft mounted in said box, a regulating-cone secured to the shaft, a conveyer-worm on the shaft and having substantially one-half of the

last turn of the worm disposed in a plane at right angles to the shaft and adjacent to the opening in the cylinder, and having its end bent at an inclination to the length of said shaft and toward the marginal edge of the adjacent turn of the worm, whereby grain may be compacted or choked within the cylinder, as set forth.

In testimony whereof we hereunto affix our signatures in presence of two witnesses.

SAMUEL S. FOOTE.
JOSEPH C. MCKEE.
